DIRECT-CURRENT VIBRATORY MOTOR.

1,396,336.

Specification of Letters Patent.

Patented Nov. 8, 1921.

Application filed December 28, 1916. Serial No. 139,334.

To all whom it may concern:

Be it known that I, LESLIE R. McDONALD, a citizen of the United States, and resident of Montreal, in the Province of Quebec and Dominion of Canada, have invented new and useful Improvements in Direct-Current Vibratory Motors, of which the following is a specification.

This application is in part a continuation 10 of my prior application filed June 16, 1916, S. N. 104,095.

The principal object of this invention is to adapt a motor of the general character referred to to be operated with direct current. Another object of the invention is to provide means for interrupting the direct current at the proper frequency and time intervals continuously to vibrate the vibratory members. Another object is to provide 20 a plurality of means for interrupting the current, the means being so associated together that they may be operated either separately or in conjunction to open and close the circuit at the proper intervals of time 25 with respect to the vibration of the vibratory members. Another object of the invention is to employ the vibratory members for controlling the application of the recurrent force driving the members. A further 30 object is to employ vibratory means tuned to vibrate in synchronism with the vibratory members for controlling the application of the recurrent force. And still a further object is to associate the vibratory controlling 35 means with the means for driving the vibratory members of the motor so that both the vibratory means and the vibratory members are driven by the same means.

Other objects of the invention will be apparent from the following description taken with the accompanying drawings in which—

Figure 1 is a plan view of one embodiment of the invention;

Fig. 2 is a vertical longitudinal section 45 taken on line 2—2 of Fig. 1;

Fig. 3 is a left end view of the apparatus; and

Fig. 4 is a diagram illustrating one system of circuit connections for the apparatus.

The particular embodiment of the invention illustrated in the drawings comprises vibratory members 1 arranged in the form of a tuning fork and mounted on an upturned

end 2 of the supporting frame 3 by means 55 of machine screws 4. The vibratory members 1 preferably comprise two straps of metal, an outer strap 8 of magnetic material and an inner strap 9 of non-magnetic material, the two straps being brazed or otherwise connected together, preferably only at their free ends. The members are adapted to be vibrated by means of a field coil 11 surrounding an armature 12 which is mounted on the struck-up portions 13 of the frame 3. The faces 14 of the armature 12 are curved, the radius of curvature of each face being substantially equal to the length of the respective vibratory members and the center of curvature being disposed at the 60 fixed end of the corresponding vibratory member so that, as the vibratory members move to and fro along the arcuate faces 14, the air-gaps between the vibratory members and the armature remain substantially 65 constant in length. By applying a pulsatory current to the coil 11 a pulsatory magnetic flux is set up in the substantially closed magnetic circuit formed by the armature 12 and the magnetic strap 8 of the vibratory 70 members. Owing to the hysteretic effect of the magnetic flux on the magnetic portion 8, the vibratory members may be caused to vibrate back and forth in synchronism with 75 the variations in flux.

The means for converting the vibratory energy of the vibratory members into rotary motion may, for example, comprise a pulley 16 mounted on a shaft 17 which rotates in the bearing 18 threaded into the opening 19 of the frame 3, the upper end of the shaft 17 being provided with screw threads for connecting the shaft to the apparatus to be driven thereby. A belt 21 is connected at one end to one of the vibratory members 1 by means of a hook 22 for example, and at the other end, through the medium of a coil spring 23, to a bracket 24 mounted on the base of the tuning fork, the belt contacting with the periphery of the pulley through an angle of approximately 420° intermediate its ends and being held tightly in contact with the pulley by means of the spring 23. When the vibratory members move to and fro, the belt is reciprocated back and forth, thereby continuously rotating the pulley 16 in the direction of the arrow as fully explained in the aforesaid applications.

A portion 26 of one side of frame 3 is struck up and an insulating plate 27 is mounted on its outer face. Upon the insulating member 27 is mounted an electrical 5 contact spring 28 having a contact point on its free end arranged to engage the contact point 29 mounted on the idle vibratory member 1. When employing contacts 28 and 29 as the sole interrupting means, the points 10 are arranged to engage each other when the vibratory members are in the position of rest, as illustrated; but when employing contacts 28 and 29 in conjunction with other interrupting means hereinafter described, the 15 contacts may be arranged to open and close when the vibratory member is at a position either somewhat within or without the position of rest. This contacting means is preferably associated with the idle vibratory member 1 so that one of the vibratory members is employed to drive the rotary member and the other vibratory member is employed to open and close the supply circuit in synchronism with the vibration of 20 the members, the two ends of the tuning fork vibrating in synchronism when they have approximately the same period of vibration. 25

Additional interrupting means comprising contacts 31 and 32 are preferably mounted 30 on an insulating plate 33 which in turn is secured to the upturned end 34 of frame 3 by means of machine screws 35. Contact 31 is in the form of a spring mounted on the angular magnetic member 36 and arranged 35 to vibrate between contact 32 and stop 37, the stop 37 being mounted on an angular magnetic member 38 similar to 36. The contact 32 is preferably threaded through a spring member 39 which is mounted on the 40 insulating plate 34 by means of a binding post 41. The fixed end of the vibrating spring 31 is connected to a binding post 42 through conductor 43. The spring 31 is preferably tuned to vibrate in synchronism 45 with the vibratory members 1.

The angular magnetic members 36 and 38 are mounted on the ends of insulating plate 33 by means of machine screws 40 so that the ends of the members extend into 50 contact with or at least into immediate proximity with the armature 12. A shunt magnetic circuit is thus provided which consists of the magnetic members 36 and 38 and the vibratory member 31. Member 31 is arranged normally to contact with contact 32, thus leaving a gap in the shunt magnetic circuit between the member 31 and the end 55 of member 38. As magnetic flux is directed through this shunt circuit by current flowing in coil 11, the spring 31 tends to move outwardly to close the aforesaid gap in the shunt, and in moving outwardly opens the circuit at contact 32. When the circuit is 60 opened the electro-magnet 11 is de-energized, 65 the flux dies out, and the spring 31 springs

back into contact with screw 32, this action being continued in synchronism with the vibrations of the vibratory members produced by the electromagnet 11. In this connection it is to be noted that the frame 3 may be 70 formed of non-magnetic material, such as brass or hard rubber, if it is desired to avoid shunting the armature 12 through the portions 13 of the frame.

A suitable circuit arrangement for the 75 apparatus is that shown in Fig. 4, wherein the supply conductors 50 are connected to the electromagnet 11 through the medium of a circuit comprising two branches 52 and 53. The branch 52 is provided with a switch 54 80 and includes the vibrating contacts 31 and 32 illustrated in Figs. 1, 2 and 3. The branch 53 is provided with a switch 55 and includes the contacts 28 and 29 shown in Figs. 1 and 2. The branch circuit joins at 85 point 56 and at point 57, and is shunted by a circuit 58 including a condenser 59 so as to prevent sparking at the vibrating contacts. By closing switch 54 electromagnet 11 is supplied with impulses of current 90 through contacts 31 and 32; when switch 55 is closed, the electromagnet is supplied with pulsating current through contacts 28 and 29; and when both of the switches are closed, both sets of vibrating contacts may be 95 arranged conjunctively to open and close the circuit through the electromagnet.

Inasmuch as the vibrating spring 31 is tuned to vibrate in synchronism with the vibratory members, the two sets of switch 100 contacts may be so adjusted as to simultaneously open and simultaneously close the supply circuit, which is of utility under certain circumstances as for example where there is danger of one set of contacts becoming inoperative due to unfavorable atmospheric conditions or other causes. However, when employing the two interrupters in parallel, as illustrated in Fig. 4, one set of contacts is preferably arranged to close the circuit 105 at time intervals properly timed with respect to the vibration of the vibratory members, and the other set of contacts is arranged to open the circuit at the proper time intervals; that is the respective sets of contacts are 110 so positioned, tensioned, etc., that one set closes before the other set, and the latter set remains closed after the first set has opened, there being an interval of time between the first opening and the last closing during 115 which both sets of contacts are closed. This affords the advantage that the opening and closing times can be more accurately determined where one set of contacts can be regulated exclusively with respect to the time of 120 closing, and the other set exclusively with respect to the time of opening, than where a single set must be so adjusted as not only to close the circuit at the proper instant but also to open it at the proper instant, it being 130

very important to open and close the circuit at the proper instants to obtain the greatest efficiency in the operation of the motor.

In the operation of motors of my new type, that is, of the general character disclosed in this application and my copending applications above cited, I have observed that a wave motion is set up throughout the belt and, especially in larger motors, this 10 wave motion is so pronounced that an appreciable space can be observed between the pulley and the belt. My experiments lead me to believe that the greatest torque is obtained when the spring is so tensioned as to 15 produce two nodes, one at each end of the belt. The waves travel from the end of the belt connected to the vibratory member toward the opposite end of the belt, that is, toward the end connected to the spring in 20 the disclosed embodiment. If the belt be removed from the pulley and be extended in a straight line in a direction such that it makes substantially the same angle with the vibratory member as does the portion be- 25 tween the pulley and the vibratory member in the drawings, the belt may be so tensioned by means of a spring at its free end that either one or more nodes appear when the belt is allowed to be vibrated freely by 30 the vibratory member.

With the spring tensioned so as to produce a node at each end of the belt and with the belt extending in a straight line so as to vibrate unobstructedly as above described. 35 the belt bows first in one direction and then in the other direction from this straight line. As the vibratory member moves inwardly the belt bows upwardly and to the left in a direction normal to the plane of the belt 40 when at rest; and when the vibratory member moves outwardly the belt bows downwardly and to the right in the opposite direction. When the belt surrounds the pulley as illustrated in the drawings, this wave motion results in the belt being thrown radially 45 outwardly from the pulley as the vibratory member moves inwardly, whereby it may be reciprocated in a clockwise direction (Fig. 1) by the spring 23 practically out of 50 contact with the pulley; and as the vibratory member moves outwardly the belt is reciprocated in a counter-clockwise direction while tightly drawn around the pulley, thereby 55 rotating the pulley in a counter-clockwise direction. With the impulses occurring at the rate of 120 per second, the angular velocity of the pulley is substantially constant.

The above phenomena appear to be characteristic of the apparatus, and I believe 60 them to involve important principles governing the operation of the subject matter of my invention. However, it is to be understood that the theory of operation above set forth is merely the theory which I be- 65 lieve to be the true explanation of the phe-

nomena which I have observed during an extended period of operation of apparatus of the character described and that the theory is given merely for the purpose of disclosing the invention in the fullest possible 70 manner and it is not to be construed as limiting the scope of the patent in any manner whatsoever.

I claim:

1. Motor apparatus comprising driving 75 means, a vibratory member for operating the driving means, electromagnetic means for vibrating said member, and a second vi- 80 bratory member vibrating separately from the first vibrating member but controlled by the first vibratory member for recurrently supplying energy to the electromagnetic means at a period substantially equal to the period of the first vibratory member.

2. Motor apparatus comprising a rotary 85 member, oscillatory means for continuously rotating the rotary member, electromagnetic means for oscillating the oscillatory means, and circuit closing means vibrating separately from the oscillatory means for intermittently closing the circuit of the electromagnetic means, the circuit closing means being operated by the electromagnetic means and its closing being automatically synchronized with the oscillatory means. 95

3. Motor apparatus comprising an oscil- 100 latory member, means for supplying energy to said member for oscillating it, and oscil- latory means vibrating separately from the oscillatory member for controlling the supply of energy, the oscillatory means being so tuned and controlled with respect to the oscillatory member as recurrently to supply energy to the member at the proper frequency to oscillate it regularly. 105

4. Motor apparatus comprising an oscil- 110 latory member, means for supplying energy to said member for oscillating it, a device rendered operative by said energy, and oscil- latory means oscillating separately from the oscillatory member tuned to the same periodicity as the oscillatory member and controlled by the said device for intermittently interrupting the supply of energy, thereby to cause the oscillatory member to 115 oscillate in synchronism with the oscillatory means.

5. Motor apparatus comprising a driving 120 member, a driven rotating member, a flexible band operatively connecting the driving member with the driven member in such manner that the operation of the driving member sets up waves in the flexible mem- 125 ber, and tuned oscillatory means oscillating separately from the driving member for recurrently supplying energy to the driving member at a uniform rate, and a common operating coil for said member and said means.

6. Motor apparatus comprising an oscil- 130

latory driving member, a circuit for supplying energy, oscillatory means independent of the oscillatory driving member for intermittently closing the circuit, and an electro-
5 magnet responsive to the energy for actuating the oscillatory member and means.

7. Motor apparatus comprising an oscillatory driving member, a circuit for supplying energy, oscillatory means independent
10 of the oscillatory driving member for intermittently closing the circuit, and an electromagnet responsive to the energy for actuating the oscillatory member and means, the oscillatory member and means being tuned
15 to oscillate in synchronism.

8. Motor apparatus comprising a vibratory member having two free ends adapted to vibrate in synchronism, means for deriving power from one of the ends, said
20 means comprising a flexible band connected to one end of said member, a driven member in operative engagement with said band, and means for supplying energy to the vibratory member to vibrate it, the supply
25 means being intermittently rendered operative by the other free end of the vibratory member.

9. Motor apparatus comprising a vibratory member in the form of a tuning fork, said means for driving apparatus with one prong of the fork, said means comprising a flexible band normally under tension and operatively connecting one prong of said fork to a pulley to be rotated, means for supplying energy to the vibratory member to vibrate it, and means controlled by the other prong of the fork for interrupting the sup-
35

ply of energy at recurrent periods corresponding to the period of vibration of the tuning fork.

40

10. Motor apparatus comprising a vibratory member mounted intermediate its ends so that the ends vibrate in synchronism, means for supplying energy to the vibratory member to vibrate both ends, a flexible band associated with one of the vibrating ends of the member so as to be vibrated thereby, a pulley around which said flexible band is wrapped and means controlled by the other end of the member for recurrently applying the energy to the members, thereby continuously to vibrate said ends.

45

11. Motor apparatus comprising a vibratory member in the form of a tuning fork, the free ends of which have at least approximately the same period so as to vibrate in synchronism, electromagnetic means for vibrating said free ends, means including a circuit for supplying current to the electromagnetic means, a flexible band arranged to be driven by one vibrating end of said member, a pulley around which a portion of said band is wrapped to drive said pulley when said tuning fork is vibrated, and means associated with the other vibrating end of said member so as to interrupt the circuit of the current supply during a portion of each vibration of the vibrating ends for intermittently energizing the electromagnetic means at the proper frequency continuously to vibrate said members.

50
